GOLF CLUB HEAD OR THE LIKE

Ted G. Houghtaling, 541 S. State Rte. 19,
Fremont, Ohio 43420

Filed Mar. 16, 1970, Ser. No. 21,922

Term of patent 14 years

Int. Cl. D21—02

U.S. Cl. D34—5

Fig. 1.

Fig. 2.

Fig. 3.

Fig. 4.

FIG. 1 is a perspective view of a golf club head showing my new design.

FIG. 2 is a front elevational view of the face of the golf club head;

FIG. 3 is a rear elevational view showing the back of the golf club head; and

FIG. 4 is an end elevational view thereof.

I claim:

The ornamental design for a golf club head or the like, substantially as shown.
